Inventor:

UNITED STATES PATENT OFFICE.

FOREST CHENEY, OF CHICAGO, ILLINOIS, ASSIGNOR, BY MESNE ASSIGNMENTS, TO
CHENEY TALKING MACHINE COMPANY, OF CHICAGO, ILLINOIS, A CORPORATION OF
ILLINOIS.

PHONOGRAPH-REPRODUCER.

1,231,329.

Specification of Letters Patent. Patented June 26, 1917.

Application filed October 8, 1913. Serial No. 793,748.

To all whom it may concern:

Be it known that I, FOREST CHENEY, a citizen of the United States, residing at Chicago, in the county of Cook and State of Illinois, have invented certain new and useful Improvements in Phonograph-Reproducers, of which the following is a specification.

The principal object of my invention is to provide a new and improved device for reproducing sound from a record. Another object of my invention is to provide a phonograph reproducer with two diaphragms working oppositely to one another so as to give an increased intensity in the reproduction of the sound from a record. Another object of my invention is to provide mechanism for transmitting the vibrations of a reproducer stylus to two diaphragms to vibrate the latter in opposition to one another. All these objects and others will be explained and made clear in the following specification and claims, taken with the accompanying drawings in which I have illustrated two specific embodiments of my invention; it will be understood that the invention is defined in the appended claims. I now proceed to describe the two specific embodiments, which as I have stated, are shown in the drawings.

Figure 1 is an elevation.

Fig. 2 is a vertical section on the line 2 of Fig. 1 looking in the direction of the arrows.

Fig. 3 is a top plan view.

Fig. 4 is an elevation with the lower part in section of the second form of my device.

Fig. 5 is a vertical section taken on the line 5, 5 of Fig. 4 looking in the direction of the arrows.

Figs. 6, 7 and 8 are perspective views of fragmentary details.

Referring to the embodiment of my invention depicted in Figs. 1, 2 and 3, the casing 11 carries two diaphragms 13 and 13' with the respective chambers 12 and 12' behind them both opening through the passages 15 and 15' into the single central chamber 14 which leads through the conduit 16 to the sound amplifying horn not shown in the drawings.

The lever 17 has an intermediate fulcrum with pivot points supported on the bar 18 and opposite thereto, the point carried by

the bar 18 being made adjustable. At its lower end lever 17 has a sleeve 19 carrying the needle 20 adapted to be secured therein by the set screw 21. Also at its lower end the lever 17 has a laterally extending arm 22 at the extremity of which is a pin and socket connection 25 to the lever 23 fulcrumed at 24. The upper end of the lever 23 is connected at 26 to the center of the diaphragm 13.

At its upper end the lever 17 has an off-set arm 22' (opposite to 22) which connects through a pin and socket joint 25' with the lever 23' fulcrumed at 24' and connected at 26' with the diaphragm 13'.

It will be seen that as the stylus 20 is vibrated by the record, the lever 17 will be oscillated about its intermediate fulcrum and this movement will be transmitted in opposite directions through the two levers 23 and 23' to the diaphragms 13 and 13'. Thus the two diaphragms 13 and 13' will move away from one another in unison and toward one another in unison so that they will act together to produce condensations and rarefactions of the air within the chambers 12 and 12' and the intermediate connecting chamber 14.

Thus it will be seen that the sound transmitted from the vibrations of the stylus 20 will be augmented, reinforced, or intensified.

Referring now to the embodiment of my invention shown in Figs. 4 to 8, inclusive, this has a shell or casing 11 with the diaphragms 13 mounted therein similar to the form shown in Figs. 1, 2 and 3. While the vibration transmitting mechanism is different in structure, its effect is the same. On each side there is a lever 30 with its upper end 31 attached to the respective diaphragm 13. Each lever 30 is pivoted intermediately at 32 and its other end consists of a point 33, the two points 33 on the two levers 30 being directed toward each other, as shown in Fig. 5. The yoke 34 depends from the casing 11 and above this yoke 34 are two downwardly directed pivot points 35, which engage corresponding sockets 37 in the short lever 36 shown in perspective in Fig. 8. Underneath the lever 36 is a cushion 38 of rubber, beneath which is a metal plate 39 held by the shouldered screws 40 in the yoke 34.

One end of the lever 36 has a sleeve or collar 41 which carries an obliquely direct-

ed stylus 42 secured by the set screw 43. The other end of the lever 36 has V-section grooves 44 on its sides which engage respectively with the points 33 that terminate the levers 30.

In the particular embodiment of my invention shown in Figs. 4 to 8, I have shown the stylus 42 inclined to the surface of the record 45; it being assumed in this instance 10 that the record is one embodying a combined "hill and dale" cut and a "zig-zag" cut.

It will also be seen that in the embodiment of Figs. 4 to 8, the lever 36 is held in engagement with the pivot points 35 by means of pressure transmitted through the cushion 38. The degree of this pressure is adjustable by means of the screws 40. This feature is not claimed in this application.

20 It will be seen that a vibration of the point of the stylus 42 results in an up and down oscillation of the end of the lever 36 carrying the grooves 44. This up and down vibration is transmitted to the points 33, 25 and thereby through the levers 30 opposite vibrations are imparted to the diaphragms 13. The effect is the same as for the form of my invention illustrated in Figs. 1, 2 and 3.

30 I claim:

1. In a sound reproducer, two parallel diaphragms with adjacent chambers between them connected to a common sound outlet, a stylus, and mechanism from the 35 stylus to the diaphragms to make the latter vibrate oppositely.

2. In a sound reproducer, two parallel diaphragms with adjacent chambers between them connected to a common sound 40 outlet, levers connected to said diaphragms on their outer sides, a stylus, and connec-

tions from the stylus to said levers to vibrate the diaphragms oppositely.

3. In a sound reproducer, two parallel diaphragms, a stylus below the same, a lever carrying the said stylus, two additional levers pivotally and directly connected to the first mentioned lever and also connected respectively to the two diaphragms, and a common sound outlet leading from both of 50 said diaphragms.

4. In a sound reproducer, two parallel diaphragms, two pivotally mounted levers arranged oppositely adjacent the outer sides of said diaphragms, an actuating lever having a pin and socket connection with each of said levers, and a stylus mounted on said actuating lever.

5. In a sound reproducer, two parallel diaphragms, two pivoted levers normally 60 disposed in parallel planes and each connected to one of said diaphragms, an actuating lever carrying a stylus and directly connected to each of said levers whereby said diaphragms are moved toward or away 65 from each other simultaneously, and a common sound outlet leading from both of said diaphragms.

6. In a sound reproducer, two parallel diaphragms, levers connected to said diaphragms on their outer sides, an actuating lever having oppositely directed angularly disposed ends, each pivotally connected to one of said first named levers, and a stylus carried by said actuating lever.

In testimony whereof, I have subscribed my name.

FOREST CHENEY.
